[57] CLAIM

The ornamental design for a jewelry display case, as shown and described.

DESCRIPTION

FIG. 1 is a front perspective view of a jewelry display case showing our new design;

FIG. 2 is a front elevational view; and

FIG. 3 is a left side elevational view, the right side being a mirror image thereof;

The rear of the jewelry display case is plain and unornamented.

FIG. 3
